UNITED STATES PATENT OFFICE.

FRED CURTISS WHITE, OF LOS ANGELES, CALIFORNIA, ASSIGNOR TO DORADO CLUB BEVERAGE CO., OF LOS ANGELES, CALIFORNIA, A CORPORATION OF CALIFORNIA.

DESIGN FOR A COMBINED BOTTLE DISPLAY AND STATUETTE.

Application filed June 25, 1928. Serial No. 27,272. Term of patent 14 years.

To all whom it may concern:

Be it known that I, FRED CURTISS WHITE, a citizen of the United States, residing at 241 South Coronado St., Los Angeles, in the county of Los Angeles and State of California, have invented a new and original and ornamental Design for a Combined Bottle Display and Statuette, of which the following is a specification, reference being had to the accompanying drawing, forming part hereof.

Figure 1 is a front elevation of the article, and Fig. 2 is a side elevation, showing my new design.

I claim:

The ornamental design of a combined bottle display and statuette as shown.

FRED CURTISS WHITE.
